UNITED STATES PATENT OFFICE.

HERMAN L. WAGNER, OF MOUNT VERNON, NEW YORK, ASSIGNOR TO UNDERWOOD TYPEWRITER COMPANY, OF NEW YORK, N. Y., A CORPORATION OF NEW JERSEY.

TYPE-WRITING MACHINE.

No. 853,281.

Specification of Letters Patent.

Patented May 14, 1907.

Application filed October 2, 1906. Serial No. 337,076.

To all whom it may concern:

Be it known that I, HERMAN L. WAGNER, a citizen of the United States, residing in Mount Vernon, in the county of Westchester and State of New York, have invented certain new and useful Improvements in Type-Writing Machines, of which the following is a specification.

This invention relates principally to that class of tabulating mechanisms for typewriting and other machines in which independently operable denomination keys are provided, although certain features thereof may be applied to other tabulating mechanisms.

My invention is in the nature of an improvement upon the construction shown in my pending application No. 323,588, filed June 27th, 1906, in which the denomination keys are shown mounted in a row on the ends of short arms which extend forwardly from the front bar of the paper carriage, denomination stops being rigidly connected to said arms and depressible independently one of another by the keys to engage column stops provided upon the framework; said denomination stops placed side by side at letter space intervals, and each key arm with its stop forming a bail, the bails being of graduated sizes and nested together in two sets, and key-bearing arms diverging or fanning out at each side of the set of stops to compensate for the greater length of the row of keys.

One object of the invention is to form and dispose the bails so that the keys shall stand in regular denominational order, preferably with the key of the highest denomination at the left of the system. To this end I place some of the keys directly upon the stop arms, while the bails for the remaining keys cross one another, so that their keys may have the proper order in the row, even though they are mounted upon the outer bail-arms nested all upon the inner or stop-arms. In each of the two sets of bails are comprised a large bail carrying a key upon its stop-arm, a second bail nested within said large bail and also carrying a key upon its stop-arm, and a plurality of crossed bails nested within said second bail and carrying keys upon their outer arms.

Another object of the invention is to make provision for additional stops and keys; and for this purpose I provide an additional bail

in each set, thus giving two additional stop-arms, making ten stops in all, each of the extra bails crossing the four bails and having a key bearing arm, the extra keys being placed at the ends of the row. Said extra keys may however be omitted in some cases.

Another object of the invention is to prevent accidental operation of the carriage releasing bar which extends along the denomination keyboard; and to this end I provide a latch which may be moved into engagement with said bar to prevent movement thereof from normal position.

I employ a plate to cover the denomination stop mechanism, and this plate I connect with the carriage-releasing mechanism, so that the plate may also serve to release the carriage when depressed, thus corresponding in function to the release-bar shown in my said application.

Other objects and advantages will herein-after appear.

In the accompanying drawings, Figure 1 is a plan of the front upper portion of an "Underwood" typewriting machine provided with my improvements. Fig. 2 is a front elevation of the parts seen at Fig. 1 but with the hundreds key depressed. Fig. 3 is a sectional side elevation illustrating the simultaneous operation of the carriage-releasing plate or bar and a denomination key. Fig. 4 is a rear perspective view of the supports of the denomination key and the latch for the carriage-releasing cover-plate; the latter shown in dotted lines. Fig. 5 is a plan of the cover-plate showing the openings therein to receive the keys. Fig. 6 is a perspective view of two of the denomination keys and stops. Fig. 7 shows a system of ten stops with their keys; the other views showing a system of only eight stops.

The usual cylindrical platen is illustrated at 1, and is mounted upon a shifting platen frame, (not shown), the latter mounted in the usual manner upon a carriage comprising side bars 2 and front bar 4. The carriage is propelled by the usual spring barrel 5 and strap 6, and is provided with a letter spacing rack 7 to mesh with a pinion 8, the latter forming part of the usual escapement or letter feeding mechanism. Said rack is usually provided at its ends with a pair of arms 9 hinged at 10 upon the carriage frame and

provided with a forwardly extending depressible arm 11, so that by depressing the arm, the rack may be raised clear of the pinion 8, and the carriage may run along freely under the influence of the propelling spring 5. The carriage has a front roll 13 running upon a track 14.

Extending along the carriage in front of the platen is a horizontal rock shaft 15 mounted in ears 16 projecting from a bracket 17, the latter detachably secured by screws 18 upon the top of the front carriage bar 4. Said rock shaft extends through the end bar 2 of the carriage and is provided with a short arm 19, to vibrate a lever 20, and thereby depress the arm 11 of the rock frame 7, 9, and release the carriage. By means of ears 22 and screws 22 a forwardly extending plate 23 is fixed upon said shaft, so that by depressing said plate, the carriage may be released. This plate is of a size to cover the denomination-stop mechanism, to protect the same from dust.

Mounted loosely upon the carriage-releasing rock-shaft 15 between the ears 22 are two sets of bails of graduated sizes shown best at Fig. 1; the bails being nested one within another, and the sets of bails being placed side by side, each bail depressible independently of the others. The largest bail in the left hand set is numbered 24, the next 25, and the remaining bails 26 and 27. The bails in the other set are correspondingly numbered 28, 29, 30 and 31. Each bail comprises a pair of arms 32 and 33, both arms extending forwardly from the rock-shaft 15. The arms 32 are straight and parallel and mounted at letter space intervals, and form a series of eight denomination stops.

The denomination keys 34 are mounted in front of the stops upon extensions 35 which diverge forwardly from the bail-arms, such divergence being necessary where the keys are mounted in a single row as illustrated, since the length of such row is much greater than the width of the system of stops 32.

It will be seen that the stops and keys are arranged in the same order throughout the system, and that the denomination of the keys proceeds in regular order beginning at the right hand with the decimal mark and increasing to millions at the left hand end of the row.

The bails in one set correspond to those in the other, but are oppositely disposed; and it will be seen that the largest bail in each set, as 24, or 28, carries a key upon its stop-arm, one of said keys marked "1000" and the other marked "100," said keys in the middle 60 of the system. The second bails 25 and 29 are nested within said largest bails, and carry upon their stop-arms the keys "10,000" and "10." The remaining bails in each set are nested within said second bail; but it will be seen that in this instance the third bail num-

bered 26 has a key-bearing extension 35 diverging from its outer arm 33, and also that the fourth bail 27 is also nested within said second bail and crosses the third bail and also has a key-bearing extension 35 diverging 70 from its outer arm. By means of this construction and this position of the bails, ample length of bearing in axial direction is secured for even the smaller bails, while the entire set of bails is kept within a small compass. 75 Springs 36 under the outer arms of the bails return the latter to normal positions. The four middle extensions 35 are branched out from the tops of the stop-arms 32 between the ends of the latter, as seen best at Fig. 3, 80 so that the extensions when depressed may clear the adjoining stops which they overlie, as seen at Fig. 1.

The bracket 17 is formed at its rear edge with an upturned comb 37 to guide the bail-arms; and the front edge of the same plate or bracket is also bent up to form a corresponding guiding comb 38 for the same arms.

In operation, any desired denomination key is depressed, the finger at the same time pressing down the cover-plate 23 which is open immediately in rear of its front edge portion to receive the denomination keys, each key preferably having a separate opening 39 in the plate. The carriage is then drawn along by the spring 5 until arrested by the engagement of the depressed stop 32 with a column stop 40 provided upon the framework. The key and cover-plate are then relieved of pressure and the type keys manipulated in the usual manner, types 41 striking as usual on the front of the platen 1. The depressible cover-plate 23 may be used for releasing the carriage for ordinary purposes, as well as during the operation of tabulating 105 as it forms a very convenient release key. The stops 40 are adjustable along a rack 42 mounted upon the framework, as set forth in my pending application No. 315,609.

It will be seen that the keys are not only mounted at the front of the machine where they may be conveniently seen and operated, but also that they are below the line of vision, that is, the tabulating mechanism does not come between the line of writing on the platen and the eyes of the operator.

If it should be desired to prevent accidental depression of the carriage-releasing cover-plate 23, there may be employed a latch 43, Fig. 4 projecting from the end of a bar 44 120 which has horizontal slots 45 to slide upon screws 46 whereby said latch 43 may be slid under the edge of plate 23 to support the same against depression. This device may also be used for other forms of release bars or keys. A stop 47 in the form of a hook may also be provided upon said latch to limit the upward movement of the release-plate caused by a returning spring 48. The bar 44 may also serve as a stop to limit the upward 125 130

movements of the bails caused by the springs 36, Fig. 3.

As more than eight denomination keys are sometimes required, I show at Fig. 7, one 5 way of adapting the invention for the use of ten keys. This is done in this instance by adding the fifth bail 49 to each set of bails; the before-mentioned stop-arms being located between the stop-arms 32^a of said fifth 10 bails, and each of the latter crossing the outer arms of the four first bails. Each of the fifth bails has a forwardly extending divergent arm 35^a mounted at the outer side of the first four bails and carrying a denomination-key 34^a. Thus at the Fig. 7 construction the system may be regarded as comprising 15 two sets of five bails in each set.

Variations may be resorted to within the scope of my invention, and portions of my 20 improvements may be used without others.

Having thus described my invention, I claim;

1. A tabulating mechanism including a 25 system of bails nested together and hinged upon a common axis, each bail consisting of a cross-bar and a pair of arms extending from said cross-bar and both hinged upon said axis, one arm of each pair extending forwardly from said axis and forming a denomination 30 stop, said stops ranging side by side at letter space intervals, a system of finger keys materially wider than the system of stops, and forwardly diverging extensions provided upon certain of said bail-arms and bearing 35 said keys, the latter being arranged in regular denominational order.

2. A tabulating mechanism including a 40 system of bails nested together and hinged upon a common axis, each bail consisting of a cross-bar and a pair of arms extending over 45 said cross-bar and both hinged upon said axis, one arm of each pair extending forwardly from said axis and forming a denomination stop, said stops ranging side by side at letter space intervals, a system of finger keys 50 in a single row, and forwardly diverging extensions provided upon certain of said bail-arms and bearing said keys, the stops and keys being arranged in the same regular denominational order with the highest denomination 55 at the left of the system.

3. A tabulating mechanism including a 60 system of bails nested together and hinged upon a common axis, each consisting of a cross-bar and a pair of arms extending from 65 said cross-bar and both hinged upon said axis, one arm of each pair extending forwardly from said axis and forming a denomination stop, said stops ranging side by side at letter space intervals, a system of finger keys, and forwardly diverging extensions provided 70 upon certain of said bail-arms and bearing said keys, the latter being arranged in regular denominational order, said system of bails

largest in each set carrying a key upon its stop-arm, and the remaining bails in each set being nested within said largest bail.

4. A tabulating mechanism including a 75 system of bails nested together and hinged upon a common axis, each bail consisting of a cross-bar and a pair of arms extending from said cross-bar and both hinged upon said axis, one arm of each pair extending forwardly from said axis and forming a denomination 80 stop, said stops ranging side by side at letter space intervals, a system of finger keys, and forwardly directed extensions provided upon certain of said bail-arms and bearing said keys, said system of bails comprising two 85 oppositely disposed sets, the largest bail in each set carrying a key upon its stop arm, the second bail in each set nested within said largest bail and also carrying a key upon its stop arm, and the remaining bails in each set 90 being nested within said second bail and carrying keys upon their outer arms.

5. A tabulating mechanism including a 95 system of bails nested together and hinged upon a common axis, each bail having a pair of arms both hinged upon said axis, the inner arm of each pair extending forwardly from said axis and provided with a denomination stop, said stops ranging side by side at letter space intervals, a system of finger keys, and forwardly directed extensions provided upon the bail-arms and bearing said keys, the latter being arranged in regular denominational order, said system of bails comprising two 100 oppositely disposed sets, the largest bail in each set carrying a key upon its stop arm, the second bail in each set nested within said largest bail and also carrying a key upon its stop arm, the third bail in each set being nested within said second bail and having a key-bearing 105 extension diverging from its outer arm, and the fourth bail in each set being also nested within the second bail and crossing the third bail and also having a key-bearing extension diverging from its outer arm.

6. A tabulating mechanism including a 110 system of bails nested together and hinged upon a common axis, each bail having a pair of arms both hinged upon said axis, one arm of each pair extending forwardly from said 115 axis and formed at its forward end into a denomination stop, said stops ranging side by side at letter space intervals, a system of finger keys, and forwardly directed extensions provided upon the bail-arms and bearing 120 said keys, the latter being arranged in regular denominational order; certain of said extensions branching from the tops of their stop-arms at points between the ends of the latter.

7. In a typewriting machine having a column stop and a power-driven carriage, the combination of a denomination-stop mechanism mounted on the carriage and including a 125 set of independently movable keys and a set 130

of stops controlled by said keys, a depressible cover plate mounted over said denomination-stop mechanism and having openings to receive the keys, and a carriage-releasing device operable by said cover plate.

8. In a typewriting machine having a column stop and a power-driven carriage, the combination of a denomination-stop mechanism mounted on the carriage and including a set of independently movable keys and a set of stops controlled by said keys, a depressible cover plate mounted over said denomination-stop mechanism, said plate open immediately in rear of its front edge to receive said keys, and a carriage-releasing device operable by said cover plate.

9. In a typewriting machine having a power-driven carriage, a tabulating mechanism including a system of independently operable denomination stops pivoted upon a rock shaft which is mounted upon said carriage, keys rigidly connected each with one of said denomination stops, a cover plate over said stops and fixed upon said rock shaft and depressible by the finger when operating any of said keys, and a carriage-releasing device operated by said rock shaft.

10. A tabulating mechanism including bails nested together and hinged upon a common axis, each bail consisting of a cross-bar and a pair of arms extending forwardly from said cross-bar and both hinged upon said axis, one arm of each pair extending forwardly from said axis and forming a denomination stop, said stops ranging side by side at letter space intervals, and keys mounted directly upon certain of said bail arms; the largest bail carrying a key upon its stop-arm, and the remaining bails nested within said largest bail.

11. A tabulating mechanism including bails nested together and hinged upon a common axis, each bail consisting of a cross-bar and a pair of arms extending forwardly from said cross-bar and both hinged upon said axis, one arm of each pair extending forwardly from said axis and forming a denomination stop, said stops ranging side by side at letter-space intervals, and keys mounted directly upon divergent extensions provided upon certain of said bail arms; the largest bail carrying a key upon its stop arm, the second bail nested within said largest bail and also carrying a key upon its stop arm, and the remaining bails being nested within the second bail.

12. In a typewriting machine, the combination with a power-driven carriage, of a set of denomination keys mounted upon the front of said carriage and movable independently of one another, denomination stops connected to said keys, a plate or bar extending along the series of keys and close thereto, so as to be operable by the same finger that depresses any key, carriage releasing

mechanism operated by said bar, and a latch for locking said bar against accidental operation.

13. In a typewriting machine having a power-driven carriage, a tabulating mechanism comprising a system of independently operable denomination stops, keys connected each with one of said denomination stops, springs for returning said stops to normal position, a bar forming a rest against which said stops are pressed by said springs, a release bar or plate arranged in proximity to said keys to be operated by the finger when depressing said keys, and a latch formed upon said rest, the latter being movable to enable said latch to lock the release bar against depression.

14. In a typewriting machine having a column stop and a power-driven carriage, the combination of a denomination-stop mechanism mounted on the carriage and including a set of independently movable keys, and a set of stops controlled by said keys, a depressible cover plate mounted over said denomination-stop mechanism, said plate open immediately in rear of its front edge to receive said keys, a carriage-releasing device operable by said cover-plate, and a latch for locking said cover-plate against accidental depression.

15. A tabulating mechanism including a system of bails nested together and hinged upon a common axis, each bail having a pair of arms both hinged upon said axis, the inner arm of each pair extending forwardly from said axis and provided with a denomination stop, said stops ranging side by side at letter space intervals, a system of finger keys, and forwardly directed extensions provided upon the bail-arms and bearing said keys, the latter being arranged in regular denominational order, said system of bails comprising two oppositely disposed sets, the largest bail in each set carrying a key upon its stop arm, the second bail in each set nested within said largest bail and also carrying a key upon its stop arm, the third bail in each set being nested within said second bail and having a key-bearing extension diverging from its outer arm, and the fourth bail in each set being also nested within the second bail and crossing the third bail and also having a key-bearing extension diverging from its outer arm; and a fifth bail in each set; the above mentioned stop arms of said fifth bails, and each of the latter crossing the four first-mentioned bails in each set and having a forwardly extending and divergent key-bearing arm mounted at the outer side of said four bails.

16. A tabulating mechanism including bails, one arm of each bail having a stop thereon; said bails divided into two sets, certain of the bails in each set crossing one another, and keys mounted upon certain of

the bail arms and having the same order as the stops.

17. A tabulating mechanism including a system of ten bails nested together and hinged upon a common axis, each bail having a pair of arms both hinged upon said axis, one arm of each pair extending forwardly from said axis and provided with a denomination stop, said stops ranging side by side at letter space intervals, a system of finger keys, and forwardly diverging extensions provided upon the bail-arms and bearing said keys, the latter being arranged in regular denominational order, said system of bails comprising two oppositely disposed sets, the largest bail in each set carrying a key upon its stop arm, the second bail in each set nested within said largest bail and also carrying a key upon its stop arm, and the remaining bails in each set crossing one another and having key-bearing extensions on their outer arms.

18. A tabulating mechanism including a set of bails of graduated sizes nested together and hinged upon a common axis, each bail consisting of a cross bar and a pair of arms connected thereby and both hinged upon said axis, the inner arm of each pair extending forwardly from said axis and provided with a denomination-stop, and key-bearing members diverging forwardly from the bails, certain of said key-bearing members being in the form of extensions provided upon certain of the stop-arms.

35 19. A tabulating mechanism including two sets of bails hinged upon a common axis, each bail consisting of a cross bar and a pair of arms connected thereby and both hinged upon said axis, the bails in each set being of graduated sizes and nested together, the inner arm of each pair extending forwardly from said axis and provided with a denomination-stop, all of said stops being mounted at letter space intervals, the bails in one set being disposed oppositely from those in the other set, key-bearing members diverging forwardly to the left in one set of bails, and key-bearing members diverging forwardly to the right in the other set of bails, certain of 50 said key-bearing members being in the form

of extensions provided upon certain of the stop-arms.

20. A tabulating mechanism including a plurality of bails of graduated sizes nested together and hinged upon a common axis, 55 each bail consisting of a cross bar and a pair of arms connected by said cross bar and both hinged upon said axis, the inner arm of each pair extending forwardly from said axis and provided with a denomination-stop, and key-bearing members upon all of said bails; certain of said key-bearing members being in the form of extensions provided upon certain of the stop-arms.

21. A tabulating mechanism including two 65 sets of bails hinged upon a common axis, each bail consisting of a cross bar and a pair of arms connected by said cross bar and both hinged upon said axis, certain of the bails in each set being of graduated sizes and nested together, the inner arm of each pair extending forwardly from said axis and provided with a denomination-stop, all of said stops being mounted at letter space intervals, the bails in one set being disposed oppositely 75 from those in the other set, and key-bearing extensions upon certain of the stop-arms.

22. A tabulating mechanism including two sets of bails hinged upon a common axis, each bail having a pair of arms both hinged 80 upon said axis, certain of the bails in each set being of graduated sizes and nested together, the inner arm of each pair extending forwardly from said axis and provided with a denomination-stop, all of said stops being 85 mounted at letter space intervals, the bails in one set being disposed oppositely from those in the other set, key-bearing extensions diverging forwardly to the left from certain of the stop-arms in one set of bails, and key-bearing extensions diverging forwardly to the right from certain of the stop-arms in the other set of bails; said extensions branching from the tops of the stop-arms at points between the ends of the latter.

HERMAN L. WAGNER.
